SECURING DEVICE

Cooper C. Drury, Dallas, Tex.

Application November 2, 1946, Serial No. 707,431

5 Claims. (Cl. 189—35)

1

This invention relates to new and useful improvements in securing devices, and more particularly to clips for securely affixing insulating material and the like to strip steel framing members.

In building construction, it is becoming more common to utilize strip steel framing members in the form of an I-beam having a nailing groove formed therein, of the type commonly known as "Stran-Steel." These framing members may take the form of studs, joists, ribs, purlins, trimmers and the like, and other building materials can be nailed directly to the framing members, the nail being deformed and clinched as it is driven into a nailing groove provided in the members. Due to the fact that the framing members are formed of steel, it has been difficult to secure insulating material and the like between the steel frame members in the usual manner.

It is, therefore, one object of this invention to provide means for securely affixing insulating material and the like between steel framing members.

A particular object of the invention is to provide resilient clip means for attaching the tabs of strips or bats of insulating materials to steel frame members for securely maintaining such insulating materials in proper insulating position.

A further object of the invention is to provide clip means of the character described for releasably securing the insulating material to the steel framing members, whereby alterations or adjustments in the installation may be made without damaging either the frame member or the insulating material.

Still another object of the invention is to provide means for securely affixing insulating material and the like in place between steel framing members in such a manner that the installation does not interfere with the normal use of such framing members.

An important object of the invention is to provide resilient clip means for securely affixing insulating material to steel framing members which is arranged to hold the tabs on the insulating material against displacement by so clipping the tabs to the framing member that force tending to displace or free the tabs from the clip means increases the frictional gripping of the clip means.

Additional objects and advantages of the invention will be readily apparent from the reading of the following description of a device con-

2

structed in accordance with the invention, and reference to the accompanying drawings thereof, wherein:

Figure 1 is a fragmentary view, in elevation, of a section of a building wall illustrating the manner in which the securing means is affixed to the steel framing members.

Figure 2 is an enlarged transverse sectional view of the framing member showing the clip in place thereon.

Figure 3 is a side elevation of the clip constructed in accordance with the invention, and

Figure 4 is a plan view of the clip.

In the drawings, the numeral 10 designates strip steel framing members of the type commonly known as "Stran-Steel," which are formed of two substantially U-shaped or channel sections joined back to back to provide the substantially I-shaped framing members having a longitudinally extending nailing groove 11 between said sections. The web of the framing member is provided with one or more longitudinally extending convolutions 10a, whereby nails or the like driven into the groove 11 will be deformed to conform to the shape of the convolutions in the web and thus will be securely held in place in the groove. The framing members are spaced apart in the customary manner to provide a support for the walls or other portions of a building, and wall board 12 or other building material is secured to the framing members by means of nails 13 or the like driven through the wall board and into the nailing grooves 11 in said framing members.

In building construction, it is frequently desirable that heat insulating or sound reducing material be interposed between the outer layers of wall board which are secured to the framing members. In order to properly support the insulating or sound reducing material in position

between the framing members 10, some means must be provided for securing such material to the framing members. The customary insulating material consists of an elongate strip or bat

45 of wool-like material 14 enclosed in an envelope 15 of suitable chemically treated paper or the like which is provided with longitudinally extending flange-like tabs 16 at opposite edges of one of the larger surfaces of the envelope. In the 50 usual installation, these elongate marginal tabs are nailed or tacked to wood framing members to securely hold the insulating material in place between the framing members.

In making installation of the insulating material between the steel framing members, how-

ever, some other means must be provided for securing the tabs to the framing members.

A spring clip 20 formed from a single elongate piece of metal, preferably spring steel or the like, is adapted to slide over one half of the flange of the I-shaped framing member 10 to releasably clamp the tab 16 of the insulating material to the framing member. The clip is formed by bending an elongate strip of spring metal upon itself to provide an open loop 21 and an elongate outer leg 22 and a shorter inner arm 23. The end of the inner arm 23 is provided with a curved tip or finger 24 which is turned outwardly away from the outer leg 22 of the clip to facilitate entry of the flange of the framing member between the arm and the leg of the clip. The inner arm is preferably bent toward the outer leg 22 until the outer curved portion thereof is in close proximity or contact with the outer arm, whereby the clip will securely clamp any material inserted between the inner end of the arm and the leg 22. The extreme outer end of the leg 22 is provided with an inwardly turned catch or foot 25 and this foot is adapted to engage in the nailing groove 11 of the I-shaped framing member 10 to prevent displacement of the clip from the flange of the framing member, whereby the clip and the insulating material clamped thereby to the framing member are securely held in position on said framing member.

The length of the inner arm 23 is such that it contacts the inner surface of the outer leg 22 at a point short of the foot 25 on said leg, whereby said arm will terminate short of the web of the framing member and the tab 16 on the insulating material may be bent inwardly, in the manner illustrated in Figure 2, to lie parallel to the inner side of the flange of the framing member and be clamped thereagainst by said arm when the clip member is slipped onto said framing member.

Since the clip is restrained against displacement from the framing member by the engagement of the foot 25 within the nailing slot or groove 11 in the framing member, it will be seen that a force attempting to pull or otherwise displace the insulating material contained in the envelope 15 from its clamped position will cause the tab to pull against the curved tip or finger section 24 of the inner arm and will press said arm toward the flange to increase the frictional and clamping action thereof. Furthermore, the envelope 15 will tend to tear at the outer end of the finger rather than to slide inwardly toward the web of the framing member and then around the finger 24 and outwardly away from the web of the framing member. Thus, the clip is arranged to hold the tab on the insulating material against displacement by so clipping the tab to the framing member that force tending to displace or free the tab from the clip increases the frictional gripping of the clip.

The clips are applied at spaced intervals longitudinally of the framing members, the spacing being such that the insulating material will be securely held in proper insulating position but utilizing a minimum of clips.

Obviously, the clip may be readily removed from engagement with the framing member by lifting the foot catch 25 from within the nailing groove and sliding the clip outwardly off the flange. Thus, the installation may be altered or adjusted without damaging either the framing member or the insulating material, and the clip members may be repeatedly used for clipping or

clamping the insulating material to the framing members.

Since the clips are formed of flat metal strips, they lie very close against the flange of the framing member and do not materially interfere with the normal use of the framing members. Also, the clips will not prevent the entry of nails into the nailing groove in the framing member.

Furthermore, the clips are resilient and may be readily installed without special machinery, without drilling additional holes in the framing members and without interfering with the normal use of such framing members. Also, the insulating material is securely and positively held in proper insulating position between the framing members.

The foregoing description of the invention is explanatory only, and changes in the details of the construction illustrated may be made by those skilled in the art, within the scope of the appended claims, without departing from the spirit of the invention.

What I claim and desire to secure by Letters Patent is:

1. In combination, a framing member having a flange, a body of insulating material having a tab, and resilient clip means having a pair of spreadable clamping members receiving the flange of the framing member and the tab of the body of insulating material therebetween and releasably clamping the tab of the body of insulating material to the flange of the framing member.

2. In combination, a framing member having a flange, a body of insulating material having a tab, resilient clip means having a pair of spreadable clamping members receiving the flange of the framing member and the tab of the body of insulating material therebetween and releasably clamping the tab of the body of insulating material to the flange of the framing member, and means on one of the clamping members of the clip means extending beyond the end of the other clamping member and turned inwardly around the web end of the framing member to restrain displacement of the clip means therefrom.

3. In combination in a building construction, flanged strip steel framing members, bodies of insulating material having tabs disposed between said framing members, and means securing the insulating material to said framing members in proper insulating position including, a clip member formed of an elongate resilient metallic strip bent upon itself in a loop to provide an elongate leg member and a shorter clamping arm member, the free end of said arm member being resiliently urged toward said leg member and receiving the flange of the framing member and the tab of the insulating material between said arm and leg members whereby said tab is clamped to said flange, and means on the leg member engaging the framing member to restrain the clip against displacement from clamping position.

4. In combination in a building construction, flanged strip steel framing members formed of two substantially U-shaped or channel sections joined back to back to provide a substantially I-shaped framing member having a longitudinally extending nailing groove between said channel sections, bodies of insulating material having tabs thereon are disposed between said framing members, and clamping means securing the insulating material to said framing member in proper insulating position including, a clip mem-

ber formed of an elongate resilient metallic strip bent upon itself in a loop to provide an elongate flat leg member and a shorter clamping arm member, the free end of said clamping arm member being turned inwardly toward said leg member and disposed closely adjacent the central portion thereof, said clamping arm being sprung away from said leg member and receiving the flange of the framing member and the tab of the insulating material between said arm and leg member for clamping the tab to the flange, said leg member having an integral catch foot at its outer free end bent toward the side of the leg on which the arm member is positioned, said catch foot engaging in the nailing groove of the strip steel framing member and restraining the clip against displacement from clamping position on the flange of said framing member.

5. In combination, a steel framing member having a flange, and a securing clip engaged with the flange and releasably clamping material to said flange and including, a unitary member of resilient material having an elongate leg member and a shorter clamping arm member connected by a resilient loop, the free end of said clamping arm member resiliently bearing against the material and clamping it against the flange,

said clamping arm member having an outturned curved tip facilitating entry of one edge of the flange and material between said arm member and leg member whereby the flange and material are received and releasably clamped therebetween, and an integral curved catch toe on the free end of the leg member engaging the opposite edge of the flange and restraining the clip against displacement from the framing member flange.
